UNITED STATES PATENT OFFICE.

FRANCISCO CLARK, OF DURANGO, MEXICO.

BUTTON.

SPECIFICATION forming part of Letters Patent No. 633,752, dated September 26, 1899.

Application filed June 13, 1899. Serial No. 720,378. (No model.)

To all whom it may concern:

Be it known that I, FRANCISCO CLARK, a citizen of the Republic of Mexico, and a resident of Durango city and county, Republic of Mexico, have invented certain new and useful Improvements in Buttons, of which the following is a full, clear, and exact specification.

My invention relates to separable buttons, the object of my invention being to construct the button in two parts, which are easily separable and as easily assembled, to the end that the button may be quickly and easily passed through the buttonhole in which it is used, and also to provide positive locking means for the parts. It consists, essentially, in providing one of the separable parts of the button (the button-head) with a post having a locking lug or projection near its outer extremity. Within the button-head which carries the post I provide a spring, which is held in place by a disk. I provide the second part of the button with a hollow or slotted shank, the slot being so shaped as to receive the post carried by the button-head. At the lower extremity of the slot I provide a circumferential groove, within which the locking-lug on the post may turn, and a notch in the groove, which notch is adapted to receive the locking lug or projection on the post when the two parts of the button are assembled together. When the locking-lug is in position in the notch provided for it, the two parts or halves of the button are locked together and are substantially rigid, and the same effect and appearance are produced as though the button consisted of but one part.

By my invention I provide a button of simple and economical construction, not easily broken or damaged while being used, and the two parts of the button cannot of themselves become loose or detached.

Referring to the drawings forming part of this application, in which like letters of reference indicate similar parts, Figure 1 is a plan view of that part of the button provided with the post and the spring, which I call the "button-head." Fig. 2 is a sectional view of the same part, taken on line $x x$ of Fig. 1, and shows the post and the spring. Fig. 3 is a plan view of the button part to which the hollow or slotted shank is attached, which I term the "button-base;" and Fig. 4 is a sectional

view of the button-base to which the hollow or slotted shank is attached, taken on line $z z$ of Fig. 3, and shows the slotted shank and the circumferential groove at its lower extremity, in which the locking-lug of the post is made to turn. Fig. 5 is a plan view of a disk which holds the spring in position in the button-head.

In constructing my improved button I preferably construct the head portion A out of a flat plate of metal, this part being stamped or pressed out of the metal in the usual or any desired manner, this part being given any ornamental form or surface configuration desired. The sides J J and the retaining edges or flanges K K of the button-head are formed in one piece with the head proper. This is done by turning the edges of the metal plate from which the head is formed upward to form the sides J J and then bending the edges of the sides J J inwardly toward the center of the head A and in the same plane, thus forming the retaining edges or flanges K K. In these retaining edges or flanges I cut notches or apertures L L L, which permit of the passage therethrough of flanges or locking projections a, with which the edge of the disk E is provided. Having thus formed one portion of the button—*i. e.*, the button-head—I place within this button-head A a post C, extending outwardly from the bottom of the head, to which it is rigidly connected. Near the outer extremity of the post C, I provide a locking lug or projection D, which is intended to engage in a circumferential groove I, formed at the bottom of the slotted or grooved shank H in the button-base.

The disk E is constructed with a central aperture M, having a notch M' extending therefrom to allow of a passage therethrough of the top of post C, with the locking-lug D attached thereto. The disk E has, as before stated, a number of flanges a at its edges, which are so constructed that they may be made to pass through the apertures L in the retaining edges or flanges K of the button-head when it is desired to pass the disk E into or remove it from the button-head A. At both sides of the central aperture M in the disk E, but a little way from the same, I provide holes or openings a' in order that the disk E may be turned in the button-head A

by a proper instrument or tool having projections which engage in the holes a' formed in the disk E, to the end that the flanges a at the edges of the disk E will properly engage 5 with the apertures L in the retaining-flanges K, with which they correspond, and in which position the disk E may be withdrawn from the button-head A.

The disk E after it has been inserted is 10 held against accidental turning by a slight jamming of the wall of the button-head, which while preventing the disk turning does not prevent its being forced inward against the tension of the spring. It will be 15 observed that the hollow shank contacts with the plate near the center thereof, while the contact between the plate and head is at the circumference, and thus only a slight friction at the circumference is sufficient to prevent 20 the disk from turning.

Within the head is located a spring which encircles the post and which tends constantly to force the disk E outwardly against the retaining edges of the head.

25 In Figs. 3 and 4, F represents the button-base, to which the hollow or slotted shank G is attached, the shank G being provided with a slot H, which is adapted to allow the passage therethrough of the post C and the locking-lug D, attached thereto. At the bottom of the 30 shank G, I provide a circumferential groove I, within which the lug D travels until it strikes a notch I', formed in the shank G. The lug D falls into the notch I', being pressed 35 upwardly into the same by the action of the spring B, and is there retained. To cause the lug D to engage with the notch I', the button-head is passed over the button-base, the post C, with the lug D, being passed down into 40 the slotted shank G. The two parts of the button—viz., the button-head and the button-base—are then pressed together, by which action the spring B is compressed and the locking-lug D passes down inside the slotted shank 45 G to the circumferential groove I, into which it passes. The button-head is then turned

over the button-base, a half-turn being given to the two parts while still being pressed together, and as this is done the locking-lug D travels in the circumferential groove I until 50 the locking-lug D of the post C enters the notch I' in the shank G at the end of the groove I and becomes firmly fixed therein, being pressed up into the notch by the action of the spring B. When the two parts of the 55 button are being pressed together, the upper part of the shank G pushes against the disk E, which retains the spring B, causing compression of the spring.

When the two parts of the button are to be 60 separated, the button-head and the button-base are pressed toward each other by the fingers of the user until the locking-lug D passes out of the notch I', when the two parts of the button may be given a half-turn with relation to each other, the lug D during this part of the operation traveling around in the circumferential groove I. When this is done, the post C, with its locking-lug D, may be withdrawn from the slotted shank G, and the two 65 parts of the button are thus separated.

I claim—

A separable button comprising a hollow head having an inwardly-turned flange at the open edge thereof with notches in said flange, 75 a spring-pressed plate having interlocking tongues corresponding to the notches of the flange, said plate being adapted to be inserted within the head and turned to bring the tongues into locking engagement with the 80 flange, a post projecting through an opening in said plate and having a locking-lug, and a base having a hollow slotted shank with a groove, said shank being adapted to receive said post, and said groove engaging said locking-lug, substantially as described.

In witness whereof I have hereunto set my hand in presence of two witnesses.

FRANCISCO CLARK.

Witnesses:

FRANCISCO ASIMSOLO,
EBERT RAPP.
